UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 3, 1924. Serial No. 723,954.

My invention relates to mining machines.

An object of my invention is to provide an improved mining machine. Another object of my invention is to provide an improved mining machine of the flexibly fed, room and pillar type having improved means to facilitate the starting or sumping cut of such a machine. Still another object of my invention is to provide an improved means on which the machine is supported during operation for facilitating the sumping cut of the mining machine and for guarding the rapidly moving cutter bits. A further object of my invention is to provide an improved supplemental frame slidable on the mine bottom on which the machine is supported adapted for use in sumping and in the cut across the face, which is also automatically movable and adapted to be automatically maintained in position. A still further object of my invention is to provide an improved telescopic cutter bit guard for the cutter chain used with a mining machine. Still another object of my invention is to provide an improved telescopic supplemental sumping frame and cutter bit guard for a mining machine which is guided by the bottom of the cutter bar and which is of an exceedingly simple and compact form substantially no longer than the frame of the mining machine. A still further object of my invention is to provide a mechanism of the class mentioned which will be freely universally movable over the mine bottom and so avoid a pronounced difficulty found with prior devices wherein due to the construction employed the resistance to movement was at times very great and there was frequent trouble due to digging into the bottom. These and other objects and advantages of my invention will, however, hereinafter more fully appear.

In the accompanying drawings I have shown for purposes of illustration one form 45 which my invention may assume in practice.

In these drawings,—

Fig. 1 is a side elevation of a mining machine equipped with my improvement, the supplemental frame being shown in its extended or sumping position.

Fig. 2 is a plan view of the mining machine shown in Fig. 1.

Fig. 3 is a side elevation of the mining machine shown in Figs. 1 and 2, the supplemental frame being shown in its collapsed 55 or retracted position.

Fig. 4 is a transverse vertical sectional view taken substantially on line 4—4 of Fig. 1.

Fig. 5 is a detail vertical sectional view 60 taken substantially on line 5—5 of Fig. 3.

Figs. 6, 7, 8 and 9 are diagrammatic views illustrating the various operative positions of the machine and the supplemental frame.

In this illustrative form of my invention 65 I have shown a mining machine, generally designated 1, of the flexibly fed room and pillar type provided with a main frame 2 normally slidable on its bottom 3 relative to a flexible feeding member, herein a feed 70 chain 4, which is adapted to cooperate with a feed operating member or sprocket 5 rotatable on a vertical axis, and cooperating guide sprockets 6 and 7 in the usual manner. The forward end of the frame 2 carries a 75 projecting cutter bar 8 provided with a cutter chain 9 adapted to be circulated about the bar and carrying cutter bits 10. The feed operating member 5 is rotatable in opposite directions at cutting and moving 80 speeds and both the members and the cutter chain 9 are driven through suitable power connections from a motor (not shown) of any suitable type carried by the frame 2. Any other form or arrangement of feed operating members and driving mechanism 85 therefor may be used if desired.

In my improved construction I have provided a supplemental supporting frame or pan, generally designated 11, which comprises a flat elongated bottom portion or shoe portion 12, adapted to slide on the mine bottom during the operation of the machine and upstanding side portions 13, preferably in the form of cutter chain guards, provided 90 with inwardly projecting angular portions 14 guided in grooves 15 formed by a longitudinally extending plate 16 bolted, as at 17, to the opposite sides of the machine frame 2. The upper surface of the bottom portion 12 100 of the supplemental supporting frame is provided with an upstanding guide member or bracket 18 adapted to underlie the cutter bar and which is provided with laterally extend-

ing gib members 19 which are adapted to cooperate with a slotted guide 20 formed in the bottom portion of the cutter bar 8. The forward ends of the side portions 13 are provided with laterally extending lugs or eye members 21 and 22 which are adapted to be engaged by a jack 23 of any suitable form, thereby permitting the forward end of the supplemental frame 11 to be held or jacked down during the starting or sumping movement of the mining machine and causing the rear end of the mining machine to be held in an elevated position as shown in Fig. 1. In order to limit the forward movement of the supplemental frame 11, I have provided an abutment 24 at the forward end of the slotted guide 20 formed in the cutter bar 8, while the rearward movement of the supplemental frame is limited by an abutment 25 formed by the rear end of the slotted guide 20, thus preventing displacement of the supplemental supporting frame from the mining machine frame 2. To prevent the supplemental frame from telescoping with respect to the machine frame, as the machine is being fed to the face, I have provided a removable pin 26 which is engaged by the rear end of the supplemental frame as shown in Fig. 1.

30 In the use of my improved device, previous to the sumping or starting operation, the supplemental supporting frame 11 is preferably, when for example on the truck, disposed in the position shown in Figs. 1, 2 and 6 and retained in this position until properly located at the rib and with the forward end of the frame jacked down by means of the jack 23. The feed chain 4 is then extended from the feed sprocket 5 and the guide sprockets 6 and 7 forwardly along the machine and anchored by a jack (not shown) at a point adjacent the working face, in a well known manner and at either side thereof depending on whether it is desired to draw in the advance or receding portion of the feed chain during sumping. The motor is then started, causing the feed sprocket 5 to rotate, consequently causing the machine to move forwardly in the supplemental supporting frame 11 relative to the feed chain 4 and thereby causing the cutter bar to be sumped in under the coal as indicated in Fig. 7, the frame 11 telescoping relative to the machine frame 2 into the position shown in Fig. 3. The feed chain is then extended laterally relative to the machine frame 2 with its ends connected at the opposite rib in a well known manner and the machine moves relative to the feed chain transversely across the face at its cutting speed, the machine then resting on the supplemental frame 11 which in turn forms the machine shoe and slides laterally on the mine bottom, as indicated by dotted lines in Fig. 7. The ma-

chine is then angled by a take-up mechanism of the usual type (see Fig. 8) and then the cut is completed by pulling the bar from the face, the machine then sliding to rearward relative to the supporting shoe (Fig. 9) until it assumes the relation shown in Fig. 1 in which it is preferably fixed by means of the pin 23 which remains in position until the start of the next sumping cut. The machine is then hauled back to its transport truck at a slow speed (see Fig. 9) in a well known manner. It will be observed that during the sumping cut, the cutter bar 8 is guided by the bracket member 18 carried by the frame 11. Attention is also directed to the fact that the upstanding sides of the frame 11 which, during the sumping cut enclose the cutter chain 9, act to prevent injury to the machine operator during the sumping cut.

As a result of my improvement it will herein be noted that I have provided a supplemental frame and guard member which are adapted to guide the machine during the sumping cut and to guard the cutter bits, thereby protecting the operator from injury, which is of exceedingly simple, rugged, and compact form, and which may be applied to a mining machine of standard construction with a minimum of change and expense. It will also be noted that I have provided an improved supplemental sumping and guarding frame which is carried by the exterior of the mining machine frame, which is guided by the bottom portion of the cutter bar, and which is substantially no longer than the frame of the mining machine. It will further be noted that I have provided a construction in which the machine frame is so supported that it is really capable of the same free universal movement on the mine bottom that is practicable with a frame without any guard whatever.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mining machine comprising a main frame and a cutter bar rigidly disposed longitudinally thereoef during cutting, feeding means for sumping said bar into a face, feeding it across the same, and withdrawing it therefrom, and a rigid supplemental frame telescopically connected to said main frame and cooperating, when in extended position, with the bottom of said main frame to produce bottom engaging means supporting said entire machine, and when in telescoped

position providing a plane shoe supporting the machine frame wholly thereon for free universal movement on the mine bottom.

2. A mining machine comprising a main frame and a cutter bar rigidly disposed longitudinally thereof during cutting, feeding means for summing said bar into a face, feeding it across the same, and withdrawing it therefrom, and a rigid supplemental frame telescopically connected to said main frame and having a bottom engaging area approximately equal to the area of the bottom of said main frame and cooperating, when in extended position, with the bottom of said main frame to produce bottom engaging means supporting said entire machine, and when in telescopied position providing a plane shoe supporting the machine frame wholly thereon for free universal movement on the mine bottom.

3. A mining machine comprising a main frame and a cutter bar rigidly disposed longitudinally thereof during cutting, feeding means for summing said bar into a face, feeding it across the same, and withdrawing it therefrom, and a rigid supplemental frame telescopically connected to said main frame and cooperating, when in extended position, with the bottom of said main frame

to produce bottom engaging means supporting said entire machine, and when in telescopied position providing a plane shoe supporting the machine frame wholly thereon for free universal movement on the mine bottom, said shoe at such time engaging the bottom at the forward end of said frame, at the rear end thereof and at an intermediate point.

4. A mining machine comprising a main frame and a cutter bar rigidly disposed longitudinally thereof during cutting, feeding means for summing said bar into a face, feeding it across the same, and withdrawing it therefrom, and a rigid supplemental frame telescopically connected to said main frame and cooperating, when in extended position, with the bottom of said main frame to produce bottom engaging means supporting said entire machine, and when in telescopied position providing a plane shoe supporting the machine frame thereon for free universal movement on the mine bottom, the planes of the bottom surfaces of said frames being parallel in all relative positions of said frames.

In testimony whereof I affix my signature.

MORRIS P. HOLMES.
